UNITED STATES PATENT OFFICE.

JOHN B. VOGEL, OF NEW ORLEANS, LOUISIANA, ASSIGNOR TO HIMSELF, EMMANUEL DREIFUS, AND CHARLES L. A. DE VAUX, OF SAME PLACE, MRS. SAMUEL GOLDSTEIN, OF SALLIS, MISSISSIPPI, AND WILLIAM LLOYD BOWRON, OF NEW YORK, N. Y.

MACHINE FOR SEPARATING FIBERS FROM PLANTS.

SPECIFICATION forming part of Letters Patent No. 324,054, dated August 11, 1885.

Application filed November 20, 1884. (No model).

To all whom it may concern:

Be it known that I, JOHN B. VOGEL, a resident of New Orleans, in the parish of Orleans and State of Louisiana, have invented an Improved Machine for Separating Fibers from Plants, of which the following is a full, clear, and exact description, reference being made to the accompanying drawings, in which—

Figure 1 is a side elevation, partly in section, of my new machine. Fig. 2 is a vertical longitudinal section of the same. Fig. 3 is a top view of the same. Fig. 4 is a detail section of the carrying cylinder, showing a modification in its construction; and Fig. 5 is an end view of said cylinder.

This invention relates to improvements on the machine for separating fibers from plants which is described in Letters Patent No. 181,382, of August 22, 1876.

The present invention consists in several details of improvement, which are hereinafter more fully specified.

In the drawings, the letter A represents the frame of the machine. B and C are two transverse shafts, which are hung in that frame, and which carry the rollers D and E, respectively. These rollers are geared together by toothed wheels *a* and *b*, (see Fig. 3), if it is intended that they should mesh together, and they can be revolved by a crank-handle, *d*, or pulley, which is applied to one of the shafts.

In order to insure the proper distance between the rollers D and E, which may be greater for some fibers than for others, I hang the lower shaft, C, which carries the smaller roller, E, in separate bearings *e*, which are connected by screws *f* with fixed lugs *g*, that project from the frame of the machine—that is to say, each screw *f* is swiveled in its lug *g* and engages a nut, which projects from the bearing *e*, so that by turning the screw the bearing will be moved and with it the shaft C, bringing the latter nearer to or farther away from the shaft B, as may be required. The rollers D and E may be solid rollers, as in Fig. 2, or hollow, as indicated in Fig. 4. The roller E, which is the smaller roller, carries a series of blades or scrapers, *h*. These blades

or scrapers are secured to the roller by being attached, by means of screws or otherwise, to projecting ribs *i*, which ribs are held by their dovetail-shanks in dovetail-grooves that are formed in the bodies of the rollers. Hence, by sliding out the ribs *i*, together with the scrapers *h*, which they carry, the roller is adapted to receive another set of ribs with a different character of scrapers or blades thereon, and thus the machine can be adapted to the manipulation of different kinds of fibers. The larger scraper-roller, D, has similar projecting ribs *j*, which carry blades *k* and *l* on the opposite faces, and these blades may either be smooth-edged, or one blade, *k*, may be smooth-edged, and the other, *l*, or both, provided with a serrated edge, as is shown in Fig. 3. When the rollers D and E are not solid, but hollow, the blades can be inserted in box-like socket-pieces *m*, such as are indicated in Fig. 4, or they may be fastened to opposite sides of such box-like socket-pieces, if desired. The roller D, between the several sets of blades, is provided with cushions F. These cushions by preference are made of rubber tubing, which is placed around rods *n* in the manner shown in Fig. 2, and the several rods *n* are by springs *o* on the outer end of the roller drawn apart so as to distend the tubes F. In other words, the rods *n*, which pass through slots in the end flanges, *p*, of the roller D, are arranged in pairs, each pair receiving a tube, F, and on the outside flange of the roller the rod *n* of one pair is united to the rod *n* of the next adjoining pair by a spring, *o*, so that the two springs *o*, acting upon the rods *n*, which are in the same tube F, will draw these two rods apart, and thereby distend said tubes; or one spring is inserted between the two rods of each pair to press the rods apart and distend the tube.

Instead of making the tubing F of rubber, it may be made of leather or any other elastic material.

G H are brushes placed, respectively, near the rollers D and E, for the purpose of keeping the same clean. It will be seen that by means of the side screws, *f*, the pressure which is exerted by the rollers upon the fiber

can be regulated. By making the scrapers or blades *k l* longitudinally removable in the manner stated they can easily be exchanged and the machine altered over into a hackling-machine, in which case toothed scrapers would be used throughout without the cushions *F*, or into a beating-machine, in which case both rollers would have plain scrapers, or into a thorough cleaning-machine, in which case one roller would have plain scrapers—that is, the roller *E*—while the other would have alternating plain and serrated scrapers, and cushions between the several scrapers. The serrated scrapers, in fact, are only useful for fibrous plants which have woody cores—such as flax, hemp, jute, and ramie—while the plain scrapers suffice for Sisal hemp, aloe, agave, ixtel, Mexican pita, yucca, banana, and all fibers having no woody matter, but only pulpy or glutinous matter.

Although I have shown the machine with only one pair of rollers, *D E*, to illustrate the several features of my invention, it is clear that in practice other rollers may be added. Thus, for many plants a set of grooved cylinders for breaking or crushing the stalks before they enter the scraping device may be used.

For others more than one set of rollers *D E* may be used, all of which will readily occur

to any one skilled in the art of removing fibers 30 from plants.

I claim—

1. The roller *D*, having scraping blades, in combination with intermediate endless cushions, *F*, that are drawn over pins *n n*, substantially as described. 35

2. The roller *D*, having slotted end flanges, *p*, in combination with the rods *n*, springs *o*, and elastic endless bands *F*, each spring connecting with two of the springs, substantially 40 as described.

3. The roller *D*, having slotted end flanges, *p*, in combination with the rods *n*, springs *o*, elastic endless bands *F*, and scrapers *k l*, as specified. 45

4. The roller *E*, having dovetail-grooves, combined with the dovetail-ribs *i* set in said grooves, and with the blades *h*, which are attached to the faces of said ribs, substantially as described. 50

5. The combination of the roller *E*, having blades *h* and dovetailed ribs *i*, with the roller *D*, having blades *k l*, intervening endless cushions *F*, and with the brushes *G H*, as specified.

JOHN B. VOGEL.
